 graphie m. b. H., Berlin, Germany, a corpora-
 tion of Germany

Application May 31, 1930, Serial No. 457,830
 In Germany August 31, 1929

2 Claims. (Cl. 250—11)

It has been ascertained that horizontal antennæ offer certain advantages over vertical antennæ both for the transmission and the reception of short waves. This condition holds good particularly for directional antenna, most especially when a marked beam or bunching action is to be insured horizontally and vertically. The essence and basic element of a horizontal antenna is the horizontal dipole, and the latter itself, as known from theory, possesses a directive action. Hence, a horizontal dipole or an antenna consisting of horizontal dipoles is not readily suited for broadcast transmitters in which the main point aimed at is to insure equally or fairly good radiation in all directions or at least in several directions. Hence, if with horizontal antennæ insuring a more or less marked beam action, places located also outside the directional diagram are to be reached, then a plurality of antennæ must be alternatively used. In actual operation such alternate use may be found a handicap under certain circumstances. This would be true, for instance, of transmissions or signals of a broadcast nature which must be received and transmitted simultaneously in several directions. Now, in cases of this kind the present disclosure indicates useful ways and means obviating the said difficulty by the combination of a plurality of directive antennæ acting in various directions and which are operated alternately at a sufficiently rapid or short sequence. By the aid of such an arrangement two directive antennæ mounted at the same place but in different manner may be so combined that the directions given by the directional diagrams of both antennæ will be embraced by one transmitter or receiver.

A more complete understanding will be had of the invention from the following specification and therefrom when read with the attached drawing in which Fig. 1 shows the characteristic curve of a pair of directional aerials operated in accordance with my invention;

Fig. 2 shows an embodiment of the invention; while

45 Figs. 3 to 5 inclusive show modifications of the arrangement of Fig. 2;

In what follows reference is made to only two antennæ, though it will be understood that what is set forth may analogously be applied to any desired number of antennæ.

50 Fig. 2 illustrates the simplest arrangement. a denotes a transmitter whose intermediate-circuit coil b works upon the two coupling coils c_1 and c_2 of antennæ d_1 and d_2 , respectively. The antenna leads are alternately grounded by the agency of

the twin contact e of a relay. However, this form of construction still involves the demerit that the rate of speed at which the changes occur in the connections of the antennæ d_1 and d_2 is limited by the relay speed. An embodiment which constitutes an improvement in this respect is illustrated in Fig. 3 in which alternate detuning by the aid of the gear-wheel f is insured by virtue of the changes in capacities g_1 and g_2 brought about by the rotation of the said gear-wheel. In this manner, circuit-change rates are obtained being equal to the circumferential speed times number of teeth. Arrangements in this scheme are so chosen that the capacity g_1 must have its crest value when g_2 has its minimum value.

Another embodiment is shown in Fig. 4 in which the energy leads h_1 and h_2 are connected with the coupling coils c_1 and c_2 , said leads in turn being brought to the two directive antennæ being, for instance, of what is known as the "Christmas tree" type, wherein the sets of radiators i_1 and i_2 are arranged in a vertical plane, the planes being at right angles with respect to each other so that each set is directive in a different direction. In parallel relation to the coupler coils c_1 and c_2 is a series connection of capacities k_1 and k_2 and inductances l_1 and l_2 which are traversed by radio frequency currents. The said inductances are of the iron-cored type, the iron core being saturated alternately by auxiliary windings 2 and 4 at an audio frequency rhythm from the audio frequency source through the leads m_1 and m_2 . In the presence of saturation of the iron-cores l_1 and k_1 and l_2 , k_2 are in series resonance and act as a short-circuit in parallel to the coupling coils c_1 and c_2 . Hence, at the instants when the audio frequency current is one of the auxiliary windings 2 or 4 saturates the core of said winding the series circuit associated therewith will be series resonant to the radio frequency current from a and will short-circuit c_1 or c_2 and the corresponding antenna will not radiate energy.

The manner in which alternate saturation may be brought about will be evident to the man trained in the art and need not be explained here.

Fig. 5 shows an arrangement in which radio frequency amplifiers n_1 and n_2 are associated with the coupling coils c_1 and c_2 , said amplifiers in turn feeding amplified energy to the antennæ i_1 and i_2 . The amplifier stages n_1 and n_2 include transmitter tubes which are alternately rendered operative and inoperative by changing the value of the potential applied to the grid electrodes of the tubes. It is well known that such an alternate change in operation can be produced at

rather high frequency, and this is a problem which is identical with the modulation and keying problem of a transmitter.

As illustrated in Figure 5, the control grids of tubes n_1 and n_2 are supplied with equal direct current potentials from source 10 connected, as shown, with the midpoint of the secondary winding of an audio frequency transformer 12. The primary winding of 12 is energized by audio frequency currents. In this manner potentials opposite in sign are applied alternately to the control grids of tubes n_1 and n_2 . These potentials superposed on the steady direct current potential change at an audio frequency rate the operativeness of tubes n_1 and n_2 and therefore change at an audio frequency rate the degree to which the antennæ i_1 and i_2 are energized.

I claim:

1. In a directive transmission system a plurality of directive aerial systems, a feed circuit including a reactance connected with each of

said aerial systems, a single high frequency generator, means for inductively coupling said generator to all of said feed circuits simultaneously, and means for detuning said feed circuits successively at an audible frequency rate including, variable reactances connected in parallel with each of said first named reactances, and a source of audio frequency oscillations coupled to said parallel reactances to vary the same successively. 5

2. In directional radio apparatus the combination of a radiant energy generator, a plurality of independent directive aerials each connected with a feed circuit including an impedance, coupling means between each of said feed circuits and said generator, a variable impedance in parallel with each of said first named impedances, each variable impedance including an inductance in the field of a magnetic circuit, and a source of audio frequency current connected with all of said magnetic circuits. 10 15 20
